US0D1088996S

(12) **United States Design Patent** (10) **Patent No.:** **US D1,088,996 S**
(45) **Date of Patent:** **** Aug. 19, 2025**

(54) **MODEL VEHICLE BUMPER**

(71) Applicant: **TRAXXAS, L.P.**, McKinney, TX (US)

(72) Inventors: **Caleb Hix**, McKinney, TX (US); **Ross Martin**, North Richland Hills, TX (US); **Adam Cole Ewing**, McKinney, TX (US); **Otto Karl Allmendinger**, Rowlett, TX (US)

(73) Assignee: **TRAXXAS, L.P.**, McKinney, TX (US)

(**) Term: **15 Years**

(21) Appl. No.: **29/934,452**

(22) Filed: **Mar. 26, 2024**

(51) LOC (15) Cl. **21-01**

(52) U.S. Cl.

USPC **D21/561**; D12/169

(57) **CLAIM**

The ornamental design for a model vehicle bumper as shown and described.

DESCRIPTION

FIG. 1 is an upper, left, front perspective view of a model vehicle bumper showing our new design;

FIG. 2 is an upper, right, rear perspective view thereof;

FIG. 3 is a lower, right, front perspective view thereof;

FIG. 4 is a lower, left, rear perspective view thereof;

FIG. 5 is a front elevation view thereof;

FIG. 6 is a rear elevation view thereof;

FIG. 7 is a right-side elevation view thereof;

FIG. 8 is a left-side elevation view thereof;

FIG. 9 is an upper plan view thereof; and,

FIG. 10 is a lower plan view of the model vehicle bumper.

1 Claim, 7 Drawing Sheets
